US0D1041313S

(12) **United States Design Patent** (10) **Patent No.:** **US D1,041,313 S**
(45) **Date of Patent:** ** *Sep. 10, 2024

(54) **DISPENSING BOTTLE**

(71) Applicant: **Henkel AG & Co. KGaA**, Duesseldorf (DE)

(72) Inventors: **Peter Cox**, Dublin (IE); **Glenn Doogan**, Lucan Co. Dublin (IE); **Peter O'Sullivan**, Dublin (IE); **Jason Tilk**, Cleveland Heights, OH (US); **Maynard Payumo**, Parma, OH (US)

(73) Assignee: **Henkel AG & Co. KGaA**, Duesseldorf (DE)

(*) Notice: This patent is subject to a terminal disclaimer.

(**) Term: **15 Years**

(21) Appl. No.: **29/850,624**

(22) Filed: **Aug. 22, 2022**

(57) **CLAIM**

The ornamental design for a dispensing bottle, as shown and described.

DESCRIPTION

FIG. 1 is a front, top, and right side perspective view of a red dispensing bottle showing our new design, where the entirety of the claimed surfaces appear at a wavelength in the range of 620-750 nm in the visible range of the electromagnetic spectrum;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof,

FIG. 8 is a front, top, and right side perspective view of a red dispensing bottle showing our new design according to another embodiment, where the entirety of the claimed surfaces appear at a wavelength in the range of 620-750 nm in the visible range of the electromagnetic spectrum;

FIG. 9 is a front view thereof;

FIG. 10 is a rear view thereof;

FIG. 11 is a left view thereof;

FIG. 12 is a right view thereof;

(Continued)

FIG. 13 is a top view thereof; and,
 FIG. 14 is a bottom view thereof.
 The broken lines depict environment and form no part of the
 claimed design.

1 Claim, 10 Drawing Sheets

Related U.S. Application Data

a continuation of application No. 29/718,433, filed on
 Dec. 24, 2019, now Pat. No. Des. 932,910.
